UNITED STATES PATENT OFFICE.

PEARL H. WILLIAMSON AND FLOYD M. WILLIAMSON, OF DETROIT, MICHIGAN, AS
SIGNORS TO WILLIAMSON & FREDERIKSON MANUFACTURING COMPANY, OF DE-
TROIT, MICHIGAN, A CORPORATION OF MICHIGAN.

WINDOW

Application filed October 14, 1926. Serial No. 141,502.

This invention relates to improvements in windows, and refers more particularly to windows wherein the sash is pivotally secured to its slides so that it may be swung about a horizontal axis at any vertical position of the slides in the stile grooves.

It is an object of the invention to provide a window wherein automatic means are provided for engaging the sides of the sash when it is moved back into alignment with the slides so as to eliminate the possibility of the sash swinging back accidentally into an inclined position.

Another object of the invention is to provide a window having positive means for preventing the sash swinging on its axis beyond a predetermined extent.

A further object of the invention is to provide a window having improved means for preventing the slides from moving vertically when the sash is in an inclined position.

Having thus briefly outlined the major purposes of the invention, I will now proceed to describe an embodiment thereof with the aid of the accompanying drawings, in which:

Figure 1 is a front elevation of a window and frame.

Figure 2 is a section on the line II--II of Figure 1, and

Figure 3 is a section on the line III--III of Figure 2.

Figure 4 illustrates a view of an angle strip, one of which is secured to the inner surface of each of the slides.

Figure 5 shows a section on the line V--V of Figure 4.

Figure 6 is a detail of the top of an angle strip and the automatic means for engaging the sash, the latter being shown slightly out of alignment with the angle strip.

Figure 7 depicts a partial view of an angle strip and the sash in an inclined position.

Figure 8 is an enlarged view showing one side of the sash and one of the slides.

Referring to the drawings, 1 designates a window frame having the usual stops 2. In the stile grooves 2^a between the stops

lower and upper slides 3 and 3^a are adapted to move vertically. To these lower and upper slides, and at their lower ends, lower and upper sashes 4 and 4^a are pivotally and detachable secured by means which will be more particularly described hereinafter. It will be noted that the upper slides 3^a are wider than the lower slides 3 so as to permit the upper sashes 4^a to swing inwards between the lower slides.

Now, since the construction of the upper and lower sashes, slides, and their co-relating parts is similar, I will describe in detail the method of construction of the lower sash, slides, and other parts connected thereto and cooperating therewith.

To the slides 3 angle strips 5 are so secured that one leg of each forms a guide for the plates 7 which extend the full length of the sash and are fastened one on each side of the latter. The plates 7 have their front edges bent over outwardly so that when the sash is in alignment with its slides these edges will each engage the front margin of one of the legs 6. The other legs 8 of the angle strips extend outwards in the stile grooves 2^a contiguous to the rear surfaces of the slides and substantially the full width of the latter.

Attached to the frame 1 between the stile grooves 2^a are weatherstrips 10 having inwardly projecting portions 9 between the legs 8 and the rear of the slides 3. The latter are grooved longitudinally as shown at 3^b to receive the forwardly flexed margins 9^a of the portions 9. Thus the portions 9 of the weatherstrips form guides positioned between the slides 3 and the legs 8 of the angle strips, and the forwardly flexed margins 9^a hold the opposed slides in spaced relation to one another.

Inside the frame 1 are the usual sash weights 12 having ordinary sash cords 13 fastened thereto. The latter pass upwards around the usual pulleys 14, down between the stops 2 and into the vertical slots 15 in the slides. Towards the top of the latter recesses 16 are provided to receive the blocks 17 which are held in position by screws 18 which pass through the legs 6 of the angle

strips 5 and are in threaded engagement with the blocks. The latter are so placed that the openings 19 through them are vertical so that the sash cords may pass through. 5 The latter after passing through the blocks extend down around the lower pulleys 20, which latter are rotatably mounted on the inner surfaces of the legs 6, through openings 21 in the plates 7, and are secured between the latter and the outer edges of the sash. 22 indicates cavities in the sides of the slides for the reception of the lower pulleys 20. Around the sash cords 13 stops 23 are secured which contact the upper surfaces 15 of the blocks 17 when the sash has been swung outwards to the desired angle. We prefer to use metal sash cords in which case the stops 23 are soldered to the cords. This arrangement of the blocks also provides 20 means for holding the sash cords in line between the upper pulleys 14 and the blocks.

On the lower end of each leg 6 a member 24 is fastened, these members 24 have outwardly projecting flanges 30 at their lower ends. Through each leg 6 and member 24 is an opening 25 which forms a bearing for its pin 26. Intermediately of their length the pins are provided with flats 27 which 30 slide into slots 28 cut in the lower ends of the plates 7. The ends of the pins adjacent to the flats are normally held in position by means of spring catches 29 mounted on the inner sides of the plates. The opposite 35 ends of the pins have cams 31 thereon, which are adapted to force spring clips 32 against the front of the stops 2. These spring clips are secured at one end of the flanges 30. In this manner the rotation of the sash is employed to force the clips in engagement with 40 the front stops to hold the sash and slides against vertical movement when the sash is in an inclined position.

When the sash 4 has been swung inwards 45 the spring catches 29 may be pulled towards one another and the ends of the pins 26 released so that the sash may be removed from between the slides.

At the upper ends of the legs 6 locking 50 members 33 are revolvably mounted. These locking members have eccentric portions 34 which are so positioned with respect to the outwardly and rearwardly flared edges of the plates 7 that the said edges make contact with the eccentric portions and cause 55 the locking members to turn as the sash swings back into alignment with the slides. The upper portions 35 of the locking members are offset outwardly so as to turn clear 60 of the edges of the plates and have inward projections 36 at the front which turn down in front of the sash as the eccentric portions are revolved. In this manner positive means 65 are provided for preventing the sash from accidentally falling back into inclined posi-

tion after having once been closed. The forward projections 36 also afford finger hold by which the locking members may be easily turned to release the sash so that it may be swung into an inclined position.

While in the foregoing the preferred form of construction has been described and shown, it is understood that the invention is susceptible to such modifications as fall within the scope of the appended claims.

What we claim as our invention and desire to secure by Letters Patent is:

1. In a window arrangement, the combination of a frame having stops therein, slides adapted to move vertically between said stops and having longitudinal grooves in their rear sides, weather strips attached to said frame and extending longitudinally between said stops, inwardly projecting portions on said weather strips, a sash pivotally mounted between said slides, angle-shaped members on said slides, one leg of each of said members being adjacent to said sash and the other leg of each of said members extending outwardly behind the inwardly projecting portions of said weather strips, and forwardly extending portions integral with the inner ends of the inwardly projecting weather strip portions taking into the longitudinal grooves in said slides.

2. In a window, the combination of a frame having stops therein, slides vertically movable between said stops, a sash between said slides having recesses in its outer margins at its lower end, plates on said outer margins having slots therethrough from their lower ends, other plates on said slides having outward flanges at their lower ends, pins rotatably mounted intermediately of their length in said slides and said other plates, said pins having flats thereon to engage said slots so that said pins and sash rotate together, spring means for holding said pins in said slots, spring members secured to said outward flanges having substantially vertical portions substantially parallel with said stops and inbent outer ends, and cams on the outer ends of said pins adapted to force the substantially vertical portions of said spring members into engagement with said stops.

3. In a window arrangement, the combination of a frame having stops therein, slides adapted to move vertically between said stops, a sash pivotally mounted between said slides, pulleys rotatably mounted on said slides, other pulleys rotatably mounted in said frame at its upper end, sash weights in said frame, sash cords having one of their ends attached to said sash, passing around said first named pulleys, up and around said other pulleys, and having their opposite ends attached to said sash weights, blocks secured to said frame between said first named pulleys and said other pulleys

having openings through them through which said sash cords pass, and stops around said cords between said blocks and said other pulleys, said cords and stops being adapted to move as said sash is swung pivotally so that the latter strike the upper side of said blocks when said sash has been swung outwards to a predetermined angle thereby limiting the pivotal movement of said sash, and said sash weights being adapted to balance said sash during its pivotal movement.
